(57) **CLAIM**

The ornamental design for planter as shown and described.

DESCRIPTION

FIG. 1 is a perspective view of a planter according to a first embodiment of the design;

FIG. 2 is a rear plan view of the planter of FIG. 1;

FIG. 3 is a front plan view of the planter of FIG. 1;

FIG. 4 is a first side view of the planter of FIG. 1;

FIG. 5 is a second side view of the planter of FIG. 1;

FIG. 6 is a top plan view of the planter of FIG. 1;

FIG. 7 is a perspective view of a planter according to a second embodiment of the design;

FIG. 8 is a rear plan view of the planter of FIG. 7;

FIG. 9 is a front plan view of the planter of FIG. 7;

FIG. 10 is a first side view of the planter of FIG. 7;

FIG. 11 is a second side view of the planter of FIG. 7; and, FIG. 12 is a top plan view of the planter of FIG. 7.

Portions of the planter shown in broken lines form no part of the claimed design.

1 Claim, 9 Drawing Sheets
